UNITED STATES PATENT OFFICE

MIRIAM GROSS, OF MILWAUKEE, WISCONSIN, ASSIGNOR TO MIRIAM GROSS COMPANY,
OF MILWAUKEE, WISCONSIN, A CORPORATION OF WISCONSIN

DESIGN FOR A KNITTED GARMENT

Application filed October 1, 1930. Serial No. 37,104. Term of patent 7 years.

To all whom it may concern:

Be it known that I, MIRIAM GROSS, a citizen of the United States, residing at Milwaukee, in the county of Milwaukee and State of Wisconsin, have invented a new, original, and ornamental Design for a Knitted Garment, of which the following is a specification, reference being had to the accompanying drawing, forming part thereof.

In the drawings:

Figure 1 is a front elevation of a knitted garment showing my invention in diagrammatic outline.

Figure 2 is a view on an enlarged scale of a fragmentary part of the design shown in

Figure 1 illustrating in detail a unitary portion of the design appearing texturally in the knitting of the skirt portion of the garment.

The design appears texturally in the outline of the contrasting types of stitches whereof the garment is knit, as well as in the relation of the texture design aforesaid to the outlines of the garment structure as a whole.

I claim:

The ornamental design for a knitted garment as shown and described.

MIRIAM GROSS.
